METHOD FOR DRILLING WELLS

Manley L. Natland, Long Beach, Calif., assignor,
by mesne assignments, of one-half to Lester
Callahan

Application June 9, 1945, Serial No. 598,574

4 Claims. (Cl. 255—1.4)

1

My invention relates to a novel method and apparatus for drilling wells and more particularly to a novel continuous coring method and apparatus suited to obtaining core specimens or sections during continued drilling.

Core specimens of the earth's strata are of inestimable value in planning and drilling oil wells and in determining subterranean geological formations, contours of oil-containing sands or oil-retaining domes, geological age of subterranean strata, prospects for oil production, geological mapping of an area, etc. No satisfactory method of obtaining sizable core specimens during continued drilling has been commercialized. Instead, present practice involves periodic or spot coring by stopping the drilling operation, withdrawing and uncoupling the drill pipe, replacing the bit with a special coring bit, recoupling and lowering the drill pipe, cutting a relatively short length of core which is retained in filamentary form in the coring bit or adjacent structure, and again withdrawing and uncoupling the drill pipe to bring the core to the surface. Much time, very considerable expense, and certain dangers are involved in such a procedure, albeit that savings of thousands of dollars could be made in drilling each well if coring could be eliminated or if core specimens could be obtained during continued drilling.

Attempts to solve the problem by analyzing the nature of the cutting raised to the surface by the circulating mud stream have not solved the problem for many reasons. The cuttings are of too small an average size, are too numerous to permit of individual inspection, even if a skilled geologist or paleontologist were constantly present, and give no indication of the slope or angle of the stratum being cut. Sizable core specimens of comparatively uniform size would be very desirable but, prior to the present invention, have not been obtainable during continuation of the drilling operation.

Much information of value is obtained from the usual core specimen taken from a well. It may indicate, for example, the slope angle of the stratum, the character of the formation, the amount of stratigraphic penetration, etc. When broken into small sections along natural cleavage planes, the resulting sections will often show fossils, shells, or petrified fish scales which are of inestimable value to a skilled paleontologist in determination of geological age, position, and history of the strata from which the sections come. Any temporary compaction or compressed

2

mass of cuttings is not a satisfactory substitute for such core sections or specimens.

The present invention has among its objects the provision of a novel method and apparatus for (1) drilling wells to obtain core specimens or sections during continued drilling, (2) for drilling in an annular zone of the well bore to leave a central core portion while providing for the breakage from this core portion of core sections and the transportation thereof to the surface of the ground, (3) for discharging sizable core sections into the stream of drilling mud or other fluid circulated in the well for transportation to the surface of the ground or other station for collection, (4) for segregation of such core sections from the usual small cuttings carried upward by this stream of mud or other fluid, etc.

As used herein, the term "core section" has reference to an actual segment or portion of a subterranean geological formation as distinct from a temporarily compressed mass of cuttings from a bit. It is an object of the invention to produce said core sections and discharge same into the circulating system of the well to be in contact with the circulated fluid and to be carried upward by the upward velocity of this fluid, typically the usual drilling mud employed in drilling of oil wells. Such drilling mud coats the core section with a protective coating facilitating its reaching the surface of the ground without undue abrasion or breakage.

It is a further object to use the mud or other circulating fluid to aid in the discharge of core sections from the drilling structure and, if desired, to aid in the breaking of a core portion along natural cleavage planes into core sections or to lubricate or protect the core sections during movement along a passage preparatory to discharge into the main stream for transportation upward in the well.

It is another object of the invention to provide a structure for cutting a core portion affixed to the bottom of the bore and for breaking this core portion into core sections in a passage means of the drilling structure. The preferred arrangement is to apply bending stresses to the core portion to break off the core portion into sections, usually along natural cleavage planes. The invention provides a novel method and apparatus for accomplishing this.

These and other objects will be apparent to those skilled in the art from the following description of an exemplary embodiment of the invention illustrated in the accompanying drawing, in which;

Fig. 1 is a view showing diagrammatically well-drilling equipment embodying one form of the invention;

Fig. 2 is a vertical cross-sectional view of the drilling unit or structure; and

Fig. 3 is a horizontal cross-sectional view taken along the line 3—3 of Fig. 2.

Referring particularly to Fig. 1, the invention is shown as being used to drill a well or bore 10 in the earth to penetrate strata suggested at 11, a portion of the well being shown cased by a casing 12. The derrick floor is suggested at 13 and carries the usual rotary drilling table 14 turned by a suitable power source, not shown, to rotate a drill column or drill stem 16 formed of sections of drill pipe 17 coupled by joints 18. The upper end of the drill stem carries the usual swivel 20, the weight of the drill stem being carried by travelling block 21 through a bail 22. The upper end of the drill stem is supplied with a fluid to be circulated in the well to aid in the cutting and in the transportation of cuttings to the surface of the ground. This fluid is, typically, a dense drilling mud supplied to the swivel 20 under high pressure and at a very considerable volume through hose 23 and pipe 24 by circulating pump 25.

The drilling structure or unit is secured to the lower end of the drill stem 16 and is indicated generally by the numeral 30. Essentially it includes a bit 31 and a driving element 32 formed either by the lowermost portion of the drill stem or, more conventionally, as a drill collar or a sub detachably connecting the bit 31 to the drill stem. The invention is illustrated as associated with a driving element comprising a sub 33 secured to the drill stem by a collar 34, but it should be clear that the invention can be adapted to other known arrangements of bit-driving element combinations.

As shown, the sub 33 is of novel form. It provides an externally threaded hub 35 threading into a cavity 36 of the bit 31 until shoulders 37 and 38, respectively, on the sub and bit, engage. At this time the hub 35 does not completely fill the cavity but leaves an annular chamber 40 bounded by a wall 41 of the cavity 36 and by a collar 42 depending from the hub 35 into a taper-ended recess 43 of the bit 31.

The bit 31 may be of any construction providing cutting elements disposed around a central passage to cut into the bottom of the well in an annular zone in a manner to leave an upstanding core portion 50 still attached to the earth and around which the cutters move to deepen the well while leaving the core portion. Merely for purpose of illustration I have shown a bit of the fish tail or type having a central passage 51 to receive the core portion 50 as cut by cutters 52 having outer and inner cutting portions 53 and 54, the latter actually determining the size of the core portion 50 and preferably extending slightly into the peripheral confines of the central passage 51 to produce a core portion that is slightly smaller in diameter than the central passage, as illustrated in Fig. 2.

In the preferred arrangement, the drilling unit provides a core passage means which functions to receive the core portion 50 to confine it while it is being broken into core sections and to deliver these core sections to the circulating fluid, typically the drilling mud, for transportation to some point of convenient inspection of the core sections, e. g., to the top of the well. In the illustrated embodiment the central passage 51

forms a part of this core passage means as does also a core passage 55 of the sub 33. This core passage communicates at one end with the central passage 51 and, at its other end, with the circulating mud stream. The core passage 55 can be considered as having a lower portion, termed a core-receiving opening 57, axially aligned with the central passage 51 of the bit and extending through the collar 42, and an upper portion, termed a core-transmitting opening 60, which angles axially from the core-receiving opening 57 and which terminates in an exit portion 61 opening on the circulating mud stream, e. g., disposed at the periphery of the sub 33 near the upper end thereof. The core-transmitting opening 60 is shown as having a curved axis angling side-wise from the axis of the core-receiving opening 57 and formed by any suitable cutting or casting operation. For example, a straight opening can be bored through a block of material, the block being subsequently bent to give the bore its curved axis and the block being then turned between the centers to the contour shown.

The drilling structure 30 provides fluid-conducting passage means spaced laterally from the core passage 55 for conducting the mud stream to the bit. Thus the sub 33 is shown as providing a plurality of fluid-conducting passages 63 communicating at their upper ends with the interior of the drill stem 16 and communicating at their lower ends with the annular chamber 40. This chamber distributes the mud to a plurality of openings 64 of the bit from which the mud discharges in washing relationship with the cutters 52. An auxiliary passage means is preferably provided to conduct a portion of the mud stream from the chamber 40 to the central passage 51 of the bit. Such an auxiliary passage is indicated by the numeral 65 and may be formed between the walls of the recesses 43 and the collar 42. The main mud stream discharging from the openings 64 picks up cuttings from the bit 31 and moves upward in the annular space between the drill stem 16 and the side wall of the well 10, as indicated by arrows 66. The mud stream rises past the exit portion 61 to receive the core sections formed as hereinafter described, carrying these upward to the top of the well. Any convenient means may be employed for separating the core sections from the drilling mud. As shown, the drilling mud moves from the casing 12 through a pipe 67, discharging onto a screen or grid 68 through which the mud and cuttings may discharge to a sump 69. If desired, a stream of water may be sprayed onto the screen 68 through a pipe 70 provided with a spray nozzle 71, this water washing the core sections retained on the screen.

The operation of the invention is as follows: during normal drilling, the bit 31 is rotated to cut into the bottom of the well in an annular zone, mud being circulated by the pump 25 to flow downward through the drill stem 16 and upward, as indicated by the arrows 66, as previously described. As cutting progresses, the cutters 54 leave the upstanding core portion 50 still secured to the subterranean formation and extending somewhat loosely in the central passage 51 of the bit. The cleavage planes of this core portion 50 usually correspond to the slope of the surrounding strata. Correspondingly, by subjecting the core portion 50 to bending stresses, it can be broken into the previously mentioned core sections.

In the illustrative embodiment the usual operation permits upward movement of the core

portion 50 relative to the downward movement of the drilling structure 30, the core portion extending somewhat loosely into the core-receiving opening 57. However, as soon as this core portion enters the axially-angling core-transmitting opening 60, it engages an arcuate wall 75 thereof to subject the core portion 50 to peripherally-applied bending stresses. This breaks a core section 76 from the upper end of the core portion, usually along naturally-occurring cleavage planes following the slope of the strata. The resulting core section 76 tends to turn with the drilling structure. To prevent abrasion between the now-severed core section 76 and the upper surface of the core portion 50 it is desirable to supply drilling mud to the central opening 51 of the bit or to the core passage 55. Some mud may enter therein by flow from the vicinity of the cutting elements 54, and this mud supply may be sufficient to produce the desired lubrication or coating of the core portion 50 and its severed core section 76. It is also desirable, however, to supply an auxiliary stream of the drilling mud, and this is accomplished, in the embodiment shown in Fig. 2, by the auxiliary passage 65 which supplies sufficient mud to the periphery of the core portion 50 to form a protective film therearound. It also tends to create an upward flow of the mud between the core portion and the walls of the core passage 55 whereby this mud is available immediately to enter the space between the severed core section 76 and the still-stationary core portion 50.

However, this auxiliary flow of mud upward through the core passage 55 need not be relied upon to discharge the core section 76 therefrom into the main mud stream, although it may have this function if desired. Even in the absence thereof it will be apparent that continued drilling will successively break the core sections 76 from the core portion 50, and that the core sections will be forced successively from the exit portion 61 to be picked up by the rising mud stream and carried to the surface of the ground. During upward transportation of the core sections 76, they will be protected by the mud from any excessive abrasive contact with the mud-confining surfaces, to the end that the core sections 76 shall reach the surface of the ground in as nearly as possible their original shape when broken from the core portion 50.

In drilling the usual oil well I find it satisfactory for most purposes to provide for a core portion 50 of a diameter about one-half inch. A diameter of approximately three-quarters inch is usually preferred and provides core sections 76 of adequate size to determine the character of the strata through which the drill is passing.

The core section 76 will break off in cylinder-like or wafer-like form, and careful checking of the angle between the face and side wall thereof will give an indication as to the slope of the strata from which the core section originated. Observation of the surfaces of such core sections will usually show valuable geological data, such as shells, petrified fish scales, etc., or these can be exposed by further breakage of the core sections after they reach the surface of the ground.

In drilling through most formations it is desirable to provide some means for applying bending stresses to the upstanding core portion 50 to break off the core sections 76. This can most conveniently be accomplished by use of the axially angling passage shown. However, in drilling through other formations, particularly when 76

using certain types of bits, the lateral vibrations of the bit in the bore hole may be sufficient to break off core sections 76 from the core portion 50. In that event the core sections will stack up in the core passage 55 and be expelled successively into the rising mud stream.

The invention comprehends the production of core sections 76 of relatively uniform size. This makes the core sections readily separable and distinguishable from the drilling mud or any chunk-like cuttings carried thereby. In addition, it provides for a regular discharge of a core section into the rising mud stream at intervals determined by the rate of drilling of the bit 31. Further, it provides for the elapse of a substantially equal time between the discharge of a core section 76 from the exit portion 61 and the time when this core section reaches the top of the ground. The core sections can thus be made to reach the top of the ground in the same sequence as they were expelled from the exit portion 61, thus leading to more accurate information as to the subterranean strata being penetrated.

From the above it will be apparent that my invention includes, among other features, the continuous coring of a well during progressive drilling. The information available from the core sections segregated at the top of the well is usually sufficient, but, if desired, the drill stem 16 can be periodically removed to install a conventional coring bit to penetrate particularly critical zones.

Various changes and modifications will be apparent to those skilled in the art from the exemplary embodiment illustrated and can be made without departing from the spirit of the appended claims.

I claim as my invention:

1. A method of drilling a well in the earth by use of a single-walled rotating drill column to which is connected a bit having a central passage, which method includes the steps of: rotating said drill column and said bit to cut into the earth in an annular zone to form a bore having a central core portion extending into said passage of said bit, said core portion having natural cleavage planes determined by the formation being drilled; forcing a stream of drilling mud downwardly inside said drill column during rotation thereof and discharging this drilling mud adjacent said bit to rise in an annular zone of said bore around said drill column; bending the upper end of said central core portion to break core sections therefrom along said natural cleavage planes, each core section being a short segment of said core portion and having a cross-sectional area substantially equal to the cross-sectional area of said core portion; moving these core sections to said annular zone and into the rising mud stream therein to be carried to the top of the well in said annular zone by the mud stream therein, the size of said annular zone being sufficient to pass said core sections without substantial rebreaking thereof during their journey to the top of the well; and separating said core sections from said drilling mud to obtain individual core sections accurately representative of the subterranean strata from which they originated.
2. A process as defined in claim 1 including the additional steps of dividing the downwardly moving mud stream into two portions, delivering one portion to the exterior of said bit to aid in its cutting, and delivering the other portion to the central passage of said bit at a posi-

tion below the top of said core portion and below the point at which said core sections are broken from said core portion to coat the core portion and the core sections as they are broken therefrom.

3. A method of continuously coring during drilling a well in the earth by use of a single-walled drill column, which method includes the steps of: drilling into the earth at a position below the bottom of said drill column and in an annular zone to form a bore and to leave an upstanding core portion in the center of the bore, said core portion having natural cleavage planes determined by the formation being drilled, said bore having an outer diameter substantially larger than said drill column to provide a relatively wide upright annular zone within the bore around said drill column; continuously forcing a stream of dense drilling mud downwardly through said drill column during continued drilling and discharging this drilling mud into the lower end of said annular zone to move as an upwardly-flowing annular stream therein to the surface of the earth; applying bending forces to the upper portion of said core portion to break periodically therefrom, along said natural cleavage planes, cylinder-like core sections; discharging said core sections into said annular stream of dense drilling mud rising in said annular zone; maintaining the upward velocity of said annular stream sufficient to carry said core sections upwardly in said annular zone, the core sections rising therein while being surrounded and protected against undue abrasion by the dense mud.

of said annular stream, the horizontal width of said annular zone being sufficient to pass said core sections without pulverization thereof whereby sizable core specimens are discharged periodically from the top of said annular zone with the mud stream; and separating these sizable core specimens from the mud stream discharging from the top of said annular zone.

4. A process as defined in claim 3, in which said core specimens are separated from said mud stream by screening, and including the step of spraying water on the core specimens during the screening thereof to remove mud therefrom.
